UNITED STATES PATENT OFFICE.

SERGE APOSTOLOFF, OF LONDON, ENGLAND, ASSIGNOR OF ONE-HALF TO WALTON FERGUSON, JR., OF NEW YORK, N. Y.

HOLLOW REINFORCED BODY.

1,234,254.

Specification of Letters Patent. Patented July 24, 1917.

Application filed December 21, 1916. Serial No. 138,231.

To all whom it may concern:

Be it known that I, SERGE APOSTOLOFF, a citizen of Great Britain, and a resident of London, England, temporarily residing in the borough of Manhattan, city, county, and State of New York, have invented certain new and useful Improvements in Hollow Reinforced Bodies, of which the following is a specification accompanied by drawings.

10. This invention relates to new and improved articles of manufacture in the form of hollow reinforced bodies or structures of cast metal, such as pots, vats, pipes, shell cases, guns, and the like.

15. The object of my invention is to produce hollow bodies, for instance of cast metal, so reinforced that they can be used for purposes to which ordinary cast metal bodies cannot be applied, as they would not have sufficient strength.

In accordance with my invention, the metal to be reinforced is cast around a metallic member, so that said member is embedded on all sides in the cast metal and incorporated with said metal. In reinforcing hollow metal structures, I prefer to use as the reinforcing member a metallic spiral and the metal for the walls of the hollow structure is cast around said spiral, so that the convolutions of the spiral are embedded in the walls of the body. This skeleton is of wire in the form of a spiral of approximately the same shape as the hollow structure to be produced, and in carrying out the method the spiral member is supported in a suitable mold and the metal is cast around the spiral in the mold, thus embedding the spiral in the walls of the hollow structure.

The mode of procedure and the examples of structures produced are illustrated in the accompanying drawings, in which—

Figure 1 is a vertical longitudinal sectional view of a shell case constructed in accordance with my invention;

45. Fig. 2 is an elevation partly in longitudinal section and partly in perspective, with portions of the cast metal walls cut away to show the formation of the spirals;

Fig. 3 is a side elevation of one of the spiral reinforcing members;

Fig. 4 is a top plan view of a plate steel disk which supports the reinforcing member;

Fig. 5 is a longitudinal sectional view

taken through the bore of a large caliber gun, and

Fig. 6 is a similar view taken through the bore of a gun of smaller caliber.

Referring to the drawings Figs. 1 to 4 inclusive show the invention applied to the manufacture of a shell case, and Figs. 5 and 6 show the invention applied to the manufacture of guns, the method of manufacture being substantially the same in both cases, and these drawings are to be taken as illustrative only, since the invention may be applied to a wide number of uses, shell cases and guns being only illustrative of two important products or structures.

One or more metallic spiral members may be used as the reinforcing member of the structure and if a plurality of spirals are used, they may be wound or combined into one reinforcing member in a variety of ways, as desired, for I am not to be understood as limiting the invention to a single spiral reinforcing member or any particular combination or arrangement of said members.

In Figs. 1 to 4 inclusive, I have chosen to show, by way of illustration, the reinforcing member shown in detail in Fig. 3, which is composed of four spirals A, B, C and D, mounted on a disk E preferably of steel, and these four spirals are wound in layers, as indicated, thus forming a cylindrical spiral structure, of the same shape as the shell casing, but of smaller diameter than the outside finished diameter of the casing. This spiral reinforcing member is suitably supported by any means well known to those skilled in the art of casting metal within a suitable mold, and the cast metal to form the walls F of the shell casing is poured around the reinforcing member, so that the spirals of said member are embedded on all sides in the metal of the walls and become incorporated with said metal. The reinforcing member is thus embedded substantially centrally in the walls F of the hollow body, and effectually reinforces the cast metal.

In some instances, as in the case of a vat or tank, the base of the structure may be cast around the base of the spiral skeleton frame, but in other instances, as with the shell case illustrated in Figs. 1 to 4 inclusive, it is preferable to build up the spiral

reinforcing member on the plate E, so that the metal of the shell case is cast upon said plate. The spiral or spirals for the reinforcing member are preferably secured to the 5 plate E as by welding.

In all cases, the wires constituting the skeleton reinforcing member should be formed of a metal having a melting point substantially the same or higher than the 10 melting point of the metal to be cast. In manufacturing a shell case in accordance with my invention, it is possible to arrange a copper driving band or bands in position in the mold, and then cast the body of the 15 case without detrimentally affecting said band.

The reinforcing member is formed of steel, preferably steel wire, and the cast metal may be of a different character, as, 20 for instance, cast iron. When I refer to a reinforcing member formed of steel wire, I mean ordinary drawn steel wire, as distinguished from rolled metal, because drawn metal has greater strength for my purposes 25 than rolled metal.

In order to absorb the oxygen or other vapors which would tend to cause bubbles or blow holes, a mixture of silicate of soda and plumbago may first be applied to the convolutions of the reinforcing member before 30 the cast metal is poured into the mold. Any other suitable preparation having the same function may also be used. When the hollow structure is to be of cast lead, the wires 35 constituting the skeleton reinforcing frame, should preferably be "tinned" before the lead is cast, in order that the lead may adhere to the reinforcing member. The hollow bodies or structures obtained in accordance 40 with this invention, have all the advantages without the disadvantages of plain unreinforced cast structures. For instance, a vessel of cast lead must have comparatively 45 thick walls or be made of an alloy of lead, in order to give it the requisite strength or rigidity, or such a vessel may be manufactured in accordance with my invention from pig lead alone with comparatively thin walls, and I retain the requisite strength 50 with great saving in weight of metal.

In Fig. 5 the manufacture of a large caliber gun is illustrated, having, in this instance, four outside diameters graduated from the breech to the muzzle, as usual in 55 such structures. At the breech portion G the spiral reinforcing members K are shown in three layers, while at the intermediate portion J the reinforcing members K are

shown in two layers. The remaining portions L and O of the gun have reinforcing 60 members in single layers, and it will be observed that the size of the wire forming the reinforcing members may be varied and graduated as found to be most efficient in the particular structure to be produced. 65

In Fig. 6 a smaller gun is shown built on substantially the same principles as the gun shown in Fig. 5.

It is to be understood that substantially the same methods of manufacture apply 70 both to the guns and shell, or to any hollow bodies made in accordance with this invention. The shell may be manufactured with one or more reinforcing coils, as shown in Fig. 5, for the illustration of the gun. 75 These coils may be placed side by side in layers before casting, or a shell or gun may be cast with one reinforcing member, then another layer cast over the first layer with the second reinforcing member, and so on. 80 In either case, the result is illustrated in Fig. 5, showing several layers of coils, however cast. The individual convolutions of the coils may also be arranged in staggered relation, as shown in Fig. 5, or in any other 85 suitable manner, and the coils may be wound, as desired, wholly in the same direction or in any other suitable way.

I claim and desire to obtain by Letters Patent the following: 90

1. As a new and improved article of manufacture, a hollow cast metal body having a metallic spiral reinforcing member of drawn steel wire embedded on all sides in its walls. 95

2. As a new and improved article of manufacture, a hollow body of cast metal having a concentric metallic spiral reinforcing member of drawn steel wire embedded on all sides in its walls and incorporated with the metal of said walls. 100

3. As a new and improved article of manufacture, a hollow cast metal body having a metallic spiral reinforcing member of drawn steel wire embedded on all sides in 105 its walls, and a base plate secured to the reinforcing member at one end and incorporated with the walls of the hollow structure.

In testimony whereof I have signed this 110 specification in the presence of two subscribing witnesses.

SERGE APOSTOLOFF.

Witnesses:

A. C. PARKHAM,
M. M. RIEHMANN.
